(57) CLAIM

The ornamental design for a merchandise display, as shown and described.

DESCRIPTION

FIG. 1 is a right perspective view of a merchandise display showing my new design;

FIG. 2 is a front and rear elevational view;

FIG. 3 is a right side elevational view;

FIG. 4 is a left side elevational view;

FIG. 5 is a top plan view; and,

FIG. 6 is a bottom plan view thereof.

The broken lines illustrated in FIGS. 1, 2, 3, 4 and 6 are for illustrative purposes only and forms no part of the claimed design.
